UNITED STATES PATENT OFFICE

CALVIN C. McGAUGH, OF ELK CITY, OKLAHOMA

DESIGN FOR A MERCHANTISING CABINET

Application filed January 14, 1931. Serial No. 38,300. Term of patent 14 years.

To all whom it may concern:

Be it known that I, CALVIN C. McGAUGH, a citizen of the United States, residing in Elk City, county of Beckham, State of Oklahoma, have invented a new, original, and ornamental Design for Merchandising Cabinets Especially Adapted for Displaying and Merchandising Hosiery, of which the following is a specification, reference being had to the accompanying drawing, forming a part thereof.

Fig. 1 is a perspective view of my new cabinet.

Fig. 2 is a horizontal section taken on the line 2—2 of Fig. 1.

I claim:

The ornamental design for a merchandising cabinet as shown.

CALVIN C. McGAUGH.
